CLOSURE FOR EXHAUST PIPES

Cline Harry Harmon and Dorathea L. Fort,
Waterloo, Iowa, assignors to Waterloo Foundry
Company, Waterloo, Iowa, a copartnership

Application May 9, 1945, Serial No. 592,902

7 Claims. (Cl. 98—59)

1
This invention relates to a closure device for protecting the open end of an upright terminal portion of an exhaust pipe of gasoline and Diesel engines, and the like.

Engines of this general class, when used out of doors, such as in tractors, farm machinery, road machinery, building and excavating apparatus, pumps and stationery power units, in the majority of instances, have a terminal portion of the exhaust pipe disposed in an upright position. Such an arrangement of the terminal portion of the exhaust pipe has long presented the annoying problem of providing some means for protecting the open end of the exhaust pipe from rain, snow, dust and dirt, when the engine is not operating. When moisture is permitted to collect in the exhaust pipe it frequently causes difficulty in starting, as well as in operation, of the engine, and also it frequently results in rapid rusting and deterioration of the exhaust pipe and other parts of the engine. Protection for the open end of exhaust pipes on engines as above referred to has, in some instances, been provided for in a make-shift fashion by the use of a tin can, if one happened to be available, for replacement over the upper end of the exhaust pipe when the engine is shut down.

The present invention in its broadest aspect contemplates, as a main object, the provision of a novel closure device for such exhaust pipes, comprising a pivoted closure flap which normally covers the open end of the pipe, and which is adapted to be moved to open position by the pressure of the exhaust gases discharging through the pipe when the engine is started, and remains in such open position by the continued pressure exerted by the exhaust gases while the engine continues to function, and the device being constructed and arranged so that said closure flap automatically closes to form a protective cover for the open end of the exhaust pipe when the engine is shut off.

Another object is to provide a novel closure device of the character indicated which is relatively simple in construction, positive in operation, economical to manufacture, and which may be quickly and easily applied to or removed from the terminal end of the exhaust pipe.

A further object is to provide a novel closure device of the character indicated comprising a frame adapted to surround the upper end of the exhaust pipe, and a closure flap pivotally connected to the frame and normally overlying the open end of the exhaust pipe and wherein the pivot connection is enclosed in a manner so

as to be fully protected from the elements as well as dust and dirt which might impair the freedom of pivotal movement of said closure flap.

5 Other objects and advantages of this invention will be apparent from the following description, taken in connection with the accompanying drawing in which:

Figure 1 is a plan view of the closure device embodying the present invention, shown mounted on the upper end of an exhaust pipe;

Figure 2 is a vertical section through the device and exhaust pipe, taken substantially as indicated at line 2—2 on Figure 1; and

15 Figure 3 is a transverse, vertical section through the device, taken substantially as indicated at line 3—3 on Figure 2.

The closure device embodying the present invention comprises a frame 10, in the form of a split ring, adapted to surround the upper end of an exhaust pipe 11, as clearly seen in Figure 2 of the drawing. The split ring includes a pair of laterally projecting, transversely spaced apart ears 12, adapted to be connected together by a bolt 14 and a nut 14a, for drawing the ears 12 together and firmly clamping the ring 10 around the exhaust pipe. Extending laterally from the ring 10, at substantially diametrically opposite relation to the ears 12, is a lug 15 to which a

20 closure flap 16 is pivotally connected. Said closure flap in the main is of circular contour and is provided with a marginal depending flange 17 adapted to surround the upper portion of the pipe 11 and seat upon the upper end of said ring 10. As shown in Figure 2 of the drawing, the ring is mounted on the exhaust pipe so that the upper end of the pipe projects slightly above the upper surface of the ring and abuts against the undersurface of the closure flap 16. If desired, however, said ring may be mounted on the

25 exhaust pipe so that in the closed position of the flap the marginal flange 17 seats upon the upper end of the ring 10, and the flap is otherwise out of contact with the end of the exhaust pipe 11.

30 The closure flap includes a rearwardly extending tail portion 20, constituting a counterweight which is recessed as indicated at 21, for the reception of the lug 15 of the ring. The side walls of the tail portion, in registration with the recessed portion 21, are disposed in close proximity to the upright surfaces of the lug 15, and are pivotally connected to said lug by a pivot pin 23. Said pivot pin extends freely through said lug 15 and its opposite ends are rigidly secured in the side walls of said tail portion 20, in registration

with the recess 21, by riveting over of the ends of the pin substantially flush with the outer surface of the side walls of the tail portion 20, as clearly indicated at 25 in Figure 1 of the drawing. Thus the pivot connection is fully enclosed and protected against the elements as well as against dust and dirt which might impair the freedom of pivotal movement of the closure flap 16 with respect to the ring 10.

The counterweight of the tail portion 20 of the flap is such as to counterbalance a substantial portion of the overhanging weight of the closure flap 16 so that said closure flap may be moved to an open position, as indicated in dot and dash outline in Figure 2, by the pressure of the exhaust gases discharging through the exhaust pipe 11. The overhanging weight of the closure flap, when the pressure of the exhaust gases is discontinued by shutting down the engine, automatically returns said flap to the full line position seen in Figure 2 of the drawing.

It is to be understood that the closure device embodying the present invention may be produced in various sizes for accommodating different diameters of exhaust pipes. While we have herein shown the closure device formed of castings, it may, if desired, be produced in the form of sheet metal stampings. It will also be apparent that in lieu of the counterweight the overhanging weight of the closure flap 16 may be partially counterbalanced by means of a spring.

While we have herein shown and described a preferred embodiment of our invention, manifestly it is capable of modification and rearrangement of parts without departing from the spirit and scope thereof. We do not, therefore, wish to be understood as limiting this invention to the precise embodiment herein disclosed, except as we may be so limited by the appended claims.

We claim as our invention:

1. In combination, an upwardly extending exhaust pipe constituting a conduit element for the exhaust gases of a gas engine, and a closure device mounted on said conduit element and comprising a frame element surrounding the upper portion of the conduit element, a laterally extending lug connected to said frame element, a closure flap normally covering the open end of said conduit element and movable to open position by the pressure of exhaust gases discharging through said conduit element, a counterweight connected to said flap and having a portion extending laterally past the axis of said pivotal connection for counterbalancing a substantial portion of the overhanging weight of the flap, said counterweight having a cavity formed in the underside thereof, said flap being mounted on the frame element with said lug fitted in said cavity with the side walls of said cavity around said lug, a pin pivotally connecting the side walls of the cavity to said lug, and stop means carried by said counterweight and adapted to abut one of said elements for limiting opening movement of the closure flap to a position for insuring movement of said closure flap toward closed position upon reduction of pressure of the exhaust gases.

2. In combination, an upwardly extending exhaust pipe constituting a conduit element for the exhaust gases of a gas engine, and a closure device mounted on said conduit element and comprising a frame element surrounding the upper portion of the conduit element, a laterally extending lug connected to said frame element, a closure flap normally covering the open end of said conduit element and movable to open position

by the pressure of exhaust gases discharging through said conduit element, a laterally extending counterweight connected to said flap for counterbalancing a substantial portion of the overhanging weight of the flap, said counterweight having a cavity formed in the underside thereof, said flap being mounted on said frame element with said lug fitted in said cavity with the side walls of said cavity around said lug, and a pin pivotally connecting the side walls of the cavity to said lug, the lower marginal edges of said side walls of the cavity constituting stop means adapted to abut one of said elements for limiting opening movement of the closure flap to a position for insuring movement of said closure flap toward closed position upon reduction of pressure of the exhaust gases.

3. For use with an upwardly extending terminal portion of an exhaust pipe of a gas engine, a closure device adapted to be mounted on the upper end of said pipe and comprising a frame in the form of a split ring adapted to surround the upper end of the pipe, means connecting the ends of said ring for clamping it firmly on the pipe, a laterally extending lug connected to said frame, a closure flap normally covering the open end of the pipe, a counterweight connected to said flap and having a portion extending laterally past the axis of said pivotal connection for counterbalancing a substantial portion of the weight of said flap, and stop means carried by the counterweight, said counterweight having a cavity formed in the underside thereof, said flap being mounted on the frame with said lug fitted in said cavity with the side walls of said cavity around said lug, a pin pivotally connecting the side walls of the cavity to said lug, and dimensioned and located relatively to said frame so as to abut the latter for limiting the opening movement of the closure flap to a position for insuring movement of said closure flap toward closed position upon reduction of pressure of said exhaust gases.

4. For use with an upwardly extending terminal portion of an exhaust pipe of a gas engine, a closure device adapted to be mounted on the upper end of said pipe and comprising a frame in the form of a ring adapted to surround the upper end of said pipe, a laterally extending lug connected to said ring, a closure flap normally covering the open end of the pipe, said flap including a portion extending over and around said lug, a pin pivotally connecting said portion of the closure flap to said lug, a counterweight connected to said portion of the flap for counterbalancing a substantial portion of the overhanging weight of said flap, and a stop feature carried by said extending portion of the flap and dimensioned and located relatively to the frame so as to abut the latter for limiting the opening movement of the closure flap to a position for insuring movement of said closure flap toward closed position upon reduction of pressure of said exhaust gases.

5. For use with an upwardly extending terminal portion of an exhaust pipe of a gas engine, a closure device adapted to be mounted on the upper end of said pipe and comprising a frame in the form of a ring adapted to surround the upper end of the pipe, a laterally extending lug connected to said ring, a flat closure flap normally covering the open end of said pipe, said flap including a counterweight extending from one side thereof, said counterweight having a cavity formed in the under-surface thereof, said flap being mounted on said frame with said lug

fitted in said cavity and with the side walls of said cavity around said lug, and a pin pivotally connecting the side walls of said cavity to said lug, said pin being fixedly secured at opposite ends in the side walls of said cavity, the lower edges of said side walls of the cavity being located relatively to said frame so as to abut the latter for limiting the opening movement of the closure flap to a position for insuring movement of said closure flap toward closed position upon reduction of pressure of said exhaust gases.

6. For use with an upwardly extending terminal portion of an exhaust pipe of a gas engine, a closure device adapted to be mounted on the upper end of said pipe and comprising a frame adapted to surround and be fixedly secured on the upper end of the pipe, a flat closure flap pivotally connected to the frame and normally covering the open end of the pipe, said flap having a peripheral flange on its underside adapted to rest on said frame and to accommodate therewithin the terminal portion of the exhaust pipe when said flap is in closed position, a counterweight connected to said flap and having a portion extending laterally past the axis of said pivotal connection for counterbalancing a substantial portion of the weight of said flap, and stop means carried by said counterweight and dimensioned and located relatively to said frame so as to abut the latter for limiting the opening movement of the closure flap to a position for insuring movement of said closure flap to a closed position upon reduction of pressure of said exhaust gases.

7. For use with an upwardly extending terminal portion of an exhaust pipe of a gas engine, a closure device adapted to be mounted on the upper end of said pipe and comprising a frame adapted to surround the upper end of the pipe, a laterally extending lug connected to said frame, a

closure flap normally covering the open end of said pipe, and movable to open position by the pressure of exhaust gases discharging through said pipe, a counterweight connected to said flap and having a portion extending laterally past the axis of said pivotal connection for counterbalancing a substantial portion of the overhanging weight thereof, said counterweight having a cavity formed in the underside thereof, said flap being mounted on the frame with said lug fitted in said cavity with the side walls of said cavity around said lug, and a pin pivotally connecting the side walls of the cavity to said lug, said counterweight being dimensioned and located relatively to said frame so as to abut the latter for limiting the opening movement of the closure flap to a position for insuring movement of the closure flap toward closed position upon reduction of pressure of said exhaust gases.
